UNITED STATES PATENT OFFICE.

JAMES T. SCHAMEL, OF PHILADELPHIA, PENNSYLVANIA.

MICROMETER SIZING-BLOCK.

1,040,774.

Specification of Letters Patent. Patented Oct. 8, 1912.

Application filed May 17, 1911. Serial No. 627,863.

To all whom it may concern:

Be it known that I, JAMES T. SCHAMEL, a citizen of the United States, residing at Philadelphia, in the county of Philadelphia and State of Pennsylvania, have invented now and useful Improvements in Micrometer Sizing-Blocks, of which the following is a specification.

The invention relates to a gaging tool, and more particularly to the class of micrometer sizing blocks.

The primary object of the invention is the provision of a device of this character in which microscopic lengths and angles may be accurately measured for the convenience of die makers, plane setters and tool workers.

Another object of the invention is the provision of a device of this character in which the gage block thereof may be accurately adjusted and locked in adjusted position, whereby the desired microscopic lengths or angles may be obtained.

A further object of the invention is the provision of a device of this character which is simple of construction, thoroughly reliable and efficient in operation, and inexpensive in manufacture.

With these and other objects in view, the invention consists in the construction, combination and arrangement of parts, as will be hereinafter more fully described, illustrated in the accompanying drawings, and pointed out in the claims hereunto appended.

In the drawings: Figure 1 is a side elevation of a device constructed in accordance with the invention, the same being partly broken away. Fig. 2 is a similar view, showing the body only thereof. Fig. 3 is an end elevation of the said body. Fig. 4 is a sectional view on the line $r-s$ of Fig. 2. Fig. 5 is a side elevation of the adjusting screw. Fig. 6 is a side elevation of the turning head removed from the screw. Fig. 7 is a side elevation of the movable gage block. Fig. 8 is a sectional view on line $8-8$ of Fig. 7. Fig. 9 is a side elevation of one of the handle sections. Fig. 10 is a side elevation of another handle section. Fig. 11 is a similar view of a further handle section. Fig. 12 is an end elevation of the guide collar for the adjusting screw. Fig. 13 is a side elevation of the binding screw detached

from the body of the device. Fig. 14 is an end view thereof.

Similar reference characters indicate corresponding parts throughout the several views of the drawings.

Referring to the drawings by numerals, 60 the device comprises a triangular-shaped base 5, preferably constructed from metal provided with a flat bottom edge 6, a forwardly inclined top edge 7, and a rear inwardly arched edge 8, the inclined top edge 65 7 being provided with a channel 9, the same being coextensive therewith and opening through opposite ends thereof to provide spaced parallel guide tracks 10, and the base of the said channel 9 is cut into to provide 70 inwardly extending arcuate shaped parallel grooves 11 forming therebetween a central web 12, the same being provided with an abutment shoulder 13 spaced from the smaller end of the base, for a purpose as will 75 be hereinafter more fully described.

The inner faces of the tracks 10 are provided with dove-tail shaped guide or runways 14, in which slidably fits a correspondingly shaped rib 15 of a movable micrometer 80 block 16, the same being formed in its top face with steps 17 and 18, respectively, the planes of which being parallel to the bottom edge 6 of the base. Formed on and at a point intermediate the ends of the rib 15 is 85 a split lug 19, provided with an internally threaded eye 20, in which is engaged an adjusting screw 21, the same being disposed in the channel 9 formed in the base 5, the rib 15 being provided with a semi-circular 90 shaped groove 22 adapted to receive one-half of the diameter of the screw when engaged in the lug 19, whereby the block 16 may be easily adjusted upon the tracks 10 at the inclined edge 7 of the base. This split lug 95 19 of the movable block 16 is provided with a binding screw 23 disposed transversely therein and is designed to tighten the lug about the adjusting screw 21, when desired.

The adjusting screw 21, at one end is reduced to form a handle extension or stem 24, and at the inner end thereof an annular shoulder 25, the handle extension or stem 24 being rotatably engaged in a centering collar 26, which is removably secured in 105 the channel 9 of the base at the rear end thereof, the said collar being held in place by means of screw members 27 passed

through opposite sides of the base 5 and engaged therewith. Detachably engaged with the handle stem or extension 24 is a cylindrical shaped hand knob 28, which latter serves to swivel the adjusting screw 21 in the collar 26, and also permits the turning of the said screw 21, when it is desired to accurately adjust the movable block 16 along the tracks 10 at the upper forwardly inclined edge of the base.

Threaded transversely through the base and extending through the central web 12 in the channel 9 thereof are reinforcing screws 29, the latter being disposed transversely and extend through opposite faces of the base. Also threaded in the base transversely thereof at a point intermediate the reinforcing screws 29 is a binding screw 30 provided with a winged head 31, and is adapted to inwardly displace the parallel tracks 10 for clamping the movable block 16 in adjusted position thereon. Normally, the movable block 16 is positioned at the smaller end of the base 5, so that its lug 25 will abut against the shoulder 13 formed in the central web 12 in the base 5, so that the steps 17 and 18 on the block will be in a plane at the lowest parallel point of adjustment thereof.

Provided in one side face of the base 5, contiguous to the top edge 7 thereof, is a graduated scale 32, the same being coöperative with a pointer mark 33 provided in the side face of the movable block 16, whereby on adjustment of the latter, the degree of movement of the same may be ascertained by the said scale 32 for the convenience of the operator of the device.

In the steps 17 and 18 of the movable block 16 are formed internally threaded sockets 34, each of which is adapted to detachably receive a vertical post, comprising a plurality of cylindrical shaped sections 35, the same being of uniform cross sectional diameter with respect to each other, and the outer surface thereof are provided with knurled portions 36, whereby the said sections may be turned for connecting the same or the detachment of one from the other. Each section 35 of the post is provided at one end with a reduced threaded lug 37 adapted for engagement within a socket 38 formed in the adjacent end of the section, contiguous thereto. Thus when the sections 35 of the post are joined together, the said post is designed to determine the height of the work. It is seen that the length of the post may be increased or decreased if desired. Also, this post is capable 60 of being connected either with the step 17 or the step 18 on the movable block 16 of the device.

The centering collar 26 with which the adjusting screw is swivelled, is provided 65 with a notch 39 having in its surface an in-

dicator mark 40, the same being adapted to register with a graduated scale 41 provided on the outer cylindrical face of the turning knob 28 at the inner end thereof, and in this manner the degree of turning 70 movement of the adjusting screw 21 may be ascertained. The turning knob 28 is provided with an outer knurled surface 42 which enables the hand of the operator to firmly grip the same for the turning of the 75 adjusting screw when setting the movable block 16 on the base 5 of the device.

It is seen that the microscopic angles and lengths may be ascertained by the device.

From the foregoing description, taken in connection with the accompanying drawings, it is thought that the construction and operation of the invention will be readily understood, without requiring a more extended explanation, and therefore the same 85 has been omitted.

What is claimed is:

1. A device of the class described, comprising a triangular-shaped base having a channel in its inclined head to provide flexing sides, a movable block slidably fitted in the channel for engagement with the inclined edge of the base, and provided with a plurality of steps containing threaded sockets, an adjusting screw swiveled at one 95 end of the channel and adjustably engaged with the block for moving the same, means flexing the sides of the base for binding the block in the channel and a post formed of separable sections, each section being provided in one end with a threaded socket and 100 on its opposite end with a threaded lug for detachably connecting the sections and also for detachably connecting the post in the threaded sockets in the steps of the block. 105

2. A device of the class described comprising a triangular shaped base having a channel in its inclined edge to provide flexing sides, a movable block slidably fitted in the channel for contacting with the inclined edge of the base, an adjusting screw swiveled at one end of the channel and adjustably engaged with the block for moving the same, a sectional post having a plurality of 110 separable parts and engageable with the block at different points thereon, and means engaging the sides of the base for locking the block in adjusted position.

3. A device of the class described comprising a triangular-shaped base having a channel in its inclined edge, a movable block slidably fitted in the channel for contacting with the inclined edge of the base, means for adjusting the block on the base, a sectional post having a plurality of separable 120 parts and engageable with the block at different points thereon, means engaging the sides of the base for the locking of the block in adjusted position, the said base being provided with a graduated scale and said 125 130

block with a pointer coöperative with the scale.

4. A device of the class described comprising a triangular-shaped base having a channel in its inclined edge, a movable block slidably fitted in the channel for contacting with the inclined edge of the base, means for adjusting the block on the base, a sectional post having a plurality of separable parts and engageable with the block at different points thereon, means engaging the sides of the base for the locking of the block in adjusted position, the said base being provided with a graduated scale, and said block with a pointer formed on the block and coöperative with the scale, and a turning knob fixed to the adjusting means for operating the same.

5. A device of the class described comprising a base having a channel in one edge thereof, a movable block slidably fitted in the channel, an adjusting screw swiveled at one end of the channel and adjustably engaged with the block for moving the same, a sectional post adapted for detachable connection with the block at different points thereon and having separable parts, the said base being provided with a graduated scale, and said block with a pointer coöperative with the scale, and a turning knob fixed to one end of the adjusting screw, the

said block being provided with a plurality of steps forming seats for the said sectional post.

6. A device of the class described comprising a triangular-shaped base having a channel in its inclined edge, a movable block slidably fitted in the channel for contact with the inclined edge of the base, an adjusting screw swiveled at one end of the channel and adjustably engaged with the block for moving the same, a sectional post detachably engaged with the block, means engaged in the base for locking the block in adjusted position, said base being provided with a graduated scale, and said block with a pointer coöperative with the scale, a turning knob fixed to one end of the adjusted screw and having a graduated scale, said block being provided with a plurality of steps forming seats for the sectional post, and a removable collar fixed to the base and centering the adjusting screw and having a pointer coöperative with the last named scale.

In testimony whereof I affix my signature in presence of two witnesses.

JAMES T. SCHAMEL.
